Primary Examiner — Austin Murphy(74) *Attorney, Agent, or Firm* — Birch, Stewart, Kolasch & Birch, LLP(57) **CLAIM**

The ornamental design for a head mounted display device, as shown and described.

DESCRIPTION

FIG. 1 is a perspective view of a head mounted display device showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a reference view thereof showing the state that the subject design has been worn around the user's neck;

FIG. 9 is a reference view thereof showing that one side of the display part (optical module) can be separated from the neck-band and the subject design can be adjusted to the face shape of the user by swivelling the display part up and down; and, FIG. 10 is a reference view thereof showing that one side of the display part (optical module) is separated from the neck-band and then attached to the user's glasses.

The broken lines depict portions of the head mounted display device that form no part of the claimed design.
